UNITED STATES PATENT OFFICE.

MADISON L. FUNK, OF MADISON, OKLAHOMA.

COLLAPSIBLE EGG-CASE.

1,081,229.

Specification of Letters Patent.

Patented Dec. 9, 1913.

Application filed June 26, 1912. Serial No. 706,015.

To all whom it may concern:

Be it known that I, MADISON L. FUNK, a citizen of the United States, residing at Madison, in the county of Beaver and State 5 of Oklahoma, have invented new and useful Improvements in Collapsible Egg-Cases, of which the following is a specification.

The general object of this invention is the provision of a novel collapsible egg case 10 which is constructed so that the same may be readily set up and assembled for use, said case being provided with a cover which is adapted to be locked in engagement therewith, said cover being adapted to receive the 15 case when in a folded position and retain the same therein, whereby the parts will be prevented from being misplaced or lost during the shipment, said case being also constructed so as to occupy a minimum amount 20 of space when not in use.

In carrying out the objects of the invention generally stated above, it will be understood, of course, that the essential features thereof are susceptible to changes in details 25 and structural arrangements, one preferred and practical embodiment being shown in the accompanying drawing, wherein:—

Figure 1 is a perspective view of the case assembled and constructed in accordance 30 with the invention. Fig. 2 is a vertical longitudinal sectional view therethrough. Fig. 3 is a transverse sectional view on the line substantially through the center of said case. Fig. 4 is a view similar to Fig. 3 35 showing the case in folded position.

Referring more particularly to the accompanying drawing in which like reference characters designate similar parts, it will be seen that the invention comprises a bottom 40 5 having extending from one of its longitudinal edges a strip 6 which is adapted to have secured thereto in any ordinary well known manner the hinges 7. One of the sides 8 of the casing is also adapted to be 45 connected to the hinges 7 whereby the said sides may be folded inwardly upon the bottom when the case is knocked down. The opposite longitudinal edge of the bottom 5 is also provided with the hinges 9 to which 50 is secured the other side 10 of the casing which is also adapted to be swung inwardly upon the bottom when the case is folded, it being understood that the side 10 is the first one to be folded upon the bottom so that the 55 side 8 may rest upon the same in a substantially flat position.

The strip 6 and the sides 8 and 10 are provided with a plurality of transversely arranged slots 11, the slots adjacent the ends of said sides being adapted to receive the 60 ends 12 of the casing which also engage similarly formed slots 13 in the bottom 5 which are adapted to register with the slots 11 of the sides. The slots intermediate the ends of the sides are adapted to receive a 65 partition 14 which is adapted to divide the case into separate compartments.

A cover 15 is provided for the case which has an annular depending flange consisting of side and end pieces 16 and 17 respectively, 70 said sides and ends being connected by the angular cleats 18 which are secured thereto by means of suitable fasteners 19. The side pieces 16 have secured to their bottom edges medially of the ends thereof the oppositely 75 disposed plates 20, said plates extending longitudinally of the said sides and having their outer surfaces flush with the bottom edges thereof. The plates 20 each have pivotally connected thereto a latch 21 which 80 is adapted to engage the elongated slot 22 formed in the plate 23 which is carried by each of the sides 8 and 10. When the latches 21 are in engagement with the slots 22 it will be seen that the cover is securely 85 retained in position upon the case and when it is desired to detach the said cover, the latches may be rotated out of engagement with the slots 22 by means of the lugs 24 formed upon the pivot ends of said latches. 90

In folding the case the cover is first removed and inverted so as to act as a receptacle. The ends 12 and partition 14 are then removed from engagement from the sides and bottom of the case and inserted into the 95 cover. The sides 10 and 8 are then folded upon the bottom in the order named and the whole is then inserted into the cover, the bottom 5 being uppermost. The latches 21 are then rotated so as to engage the bottom 100 5 thus preventing said bottom and sides from becoming detached from the cover.

From the foregoing description taken in connection with the accompanying drawing, it will be seen that the invention contemplates providing an egg case which is simple in construction thus reducing the cost of manufacture of the same to a minimum and which is durable and effective in carrying out the purpose for which it is designed. 105

What is claimed is:—

A crate comprising a box like body includ-

ing a bottom, sides hinged thereto and adapted to be folded onto the bottom in superimposed relation, ends removably secured to the bottom and adapted when in folded position to overlie and rest upon the uppermost side, and a cover having depending side and end walls, said side and end walls being spaced apart a distance corresponding to the full transverse and longitudinal dimensions of the bottom, the side and end walls being permanently secured in fixed cover forming relation, the height of said side and end walls of the cover corresponding to the thickness of the body portion in folded relation whereby said body

portion in inverted condition will be wholly housed within the cover with the lower surface of the bottom flush with the free edges of the side and end walls of the cover, and catches carried by the cover to engage the side walls of the body portion when the parts are in crate forming position and to overlie the lower surface of the bottom when the parts are in folded position.

In testimony whereof I affix my signature 25 in presence of two witnesses.

MADISON L. FUNK.
